APPARATUS FOR PRODUCING ENDLESS
EXTENDED COIL STRUCTURES

Arnold Dörr, Berlin, Germany

Application May 5, 1939, Serial No. 272,055
In Germany May 11, 1938

7 Claims. (Cl. 153—66)

This invention relates to an apparatus for producing endless extended coil structures from wire or tape. In the production of these structures it has already been proposed to wind the wire or tape about a mandrel, the said wire or tape being withdrawn from a reel or drum performing a planetary motion.

The term "extended coil structure" as employed in the present description is intended to designate a helical winding, the convolutions of which are disposed in certain spacial relation to one another, so that a so-called open winding is produced. These structures are employed for a variety of purposes. Thus, for example, short lengths thereof can be used as coil springs. If made with a sufficient diameter and cut in a length of, say, 6 to 10 feet they can be used as indoor aerials. Open windings of this nature are also employed in the construction of oil cables and serve to produce passages through which the oil is conducted to the insulating means.

In the production of extended coil structures it has already been proposed to allow the reel or drum bearing the wire or tape to move with planetary motion about a mandrel and to wind the wire or tape about the mandrel in such a way that the resulting convolutions possess the requisite spacial disposal with relation to one another.

For the production of coil structures of short length, such as coil springs or the like, either the mandrel about which the wire or tape is wound or the reel rotating about the mandrel has a longitudinal movement imparted thereto, which corresponds substantially to the length of the structure to be produced.

In the production of endless coil structures, however, this method cannot be employed, and steps require to be taken to ensure that the structure being produced is moved or conducted out of the machine steadily and continuously by suitable conveying means, to be wound, for example, on to a drum.

It has been proposed heretofore to remove the structure being produced on the mandrel from the latter by a suitable rotation of the winding drum. This method is accompanied by the disadvantage that the coil structure thus subjected to a tensile force in the longitudinal direction readily tends to be distended, whereby the spacing between the single convolutions is caused to be larger than was intended.

It has also been proposed to wrap the wire or tape in the helically disposed grooves of a rotatable and longitudinally secured spindle, so that the resulting coil structure is conveyed by the

helical spindle out of the machine. The mean diameter of the coil structure is equal to the mean diameter of the threaded spindle. This arrangement has the disadvantage that a comparatively large amount of friction results between the material from which the coil structure is being produced and the threaded spindle serving to convey the coil structure from the machine.

According to the invention these disadvantages are eliminated by the fact that the production and the conveyance of the coil structure are performed by a member which performs a rolling motion in relation to the coil structure.

The rolling member possesses a helical groove, which engages with the coil structure only at one point which passes continuously along the structure. The pitch of the helical groove is equal to the pitch of the coil. The mean diameter of the coil structure, however, is smaller or greater than the mean diameter of the helical groove in the rolling member. In consequence of the movement of a rolling member of this kind there is obtained a steady advance of the coil structure with a minimum of friction, as the rolling member rolls on or in the coil, so that there is merely a rolling friction between the coil and the rolling member.

The rolling member can be designed in the form of a sleeve, which rotates about a fixed cylindrical mandrel and at the same time about its axis. On the inner face of this sleeve there is provided the helical groove aforesaid, which engages with the coil structure in the manner referred to. The helical groove in the sleeve has the same pitch as the coil structure, although its diameter is larger.

The sleeve is mounted to be rotatable in the eccentric bore of a bush and rolls by means of internal teeth over the outer rim of teeth on a stationary mandrel.

The rolling member can also be disposed within the coil structure. It is then constructed in the form of a mandrel having a helical groove, which as before possesses the same pitch as the coil structure, but the diameter of the helical groove is smaller than that of the coil.

The mandrel rolls within a sleeve, the inner diameter of which is equal to the outer diameter of the coil structure, in order to guide the coil structure upon the advance. The mandrel is rotatable in the eccentric boring of a positively driven rotating sleeve. The rotation of the mandrel about its axis takes place by means of a gear wheel mounted on the mandrel, which gear wheel rolls over a fixed inner rim of teeth.

If it is desired to convey two superimposed coil structures, there is employed as rolling member within the coils the rotatable mandrel as described and as rolling member outside of the coils the sleeve also as described.

The invention is illustrated by way of example in the accompanying drawings, in which—

Fig. 1 is a longitudinal section through a possible embodiment of the apparatus according to the invention, wherein the rolling member is constituted by a sleeve surrounding the coil structure.

Fig. 2 is a longitudinal section through a second embodiment, in which the rolling member is represented by a mandrel disposed within the coil structure.

Fig. 3 is a section on the line III—III in Fig. 2, and

Fig. 4 is a section on the line IV—IV in Fig. 2.

In the embodiment according to Fig. 1 there is shown a fixed mandrel 1 mounted in a liner. This mandrel carries towards its rear end an externally disposed rim of teeth 2. 3 is an eccentric bush, which rotates in the direction of the arrow P. The drive is performed by means of a gear wheel (not shown) acting in conjunction with the rim of teeth 4.

Rotatable within the eccentric bush 3 is the rolling member 5, which is constituted by a sleeve having a helical groove 6 about its inner face. This helical groove possesses the same pitch as the coil structure being produced, which is formed from the wire 7. The sleeve 5 is furnished with inner teeth 8 adapted to mesh with the externally disposed teeth 2 on the mandrel 1, these inner teeth rolling over the said outer teeth and thus causing rotation of the sleeve 5. By the rotation of the eccentric bush 3 the sleeve 5 carries out an eccentric movement with respect to the fixed mandrel 1 and at the same time a rotary movement about its central axis, whereby a rolling movement is produced.

It is shown by Fig. 1 that the mean diameter of the helical groove 6 in the advancing sleeve 5 is greater than the mean diameter of the wire coil structure 7. On the other hand the pitch of the groove 6 is equal to that of the coil 7. Upon the rolling movement of the sleeve 5 along the coil 7 the helical groove 6 always contacts only with a single point of the coil, which upon the movement progresses along the coil, so that the coil is conveyed out of the apparatus, i. e., as seen in Fig. 1 in the direction towards the right. As shown by Fig. 1, the wire is fed from the source of supply to the mandrel 1 through an opening in the sleeve 5.

In the embodiment according to Figs. 2 to 4 there is shown a fixed sleeve 9. Within this sleeve there is provided a fixed cylindrical member 10, which towards the front end possesses a cylindrical recess 11, in which there is located an inner rim of teeth 12.

The front portion of the bush 9 situated towards the right in Fig. 2 is formed externally as a bearing for a rotatable sleeve 14 carrying an outer rim of teeth 15 adapted to engage with a gear wheel 16, which is driven in any suitable fashion. Rotation of the gear wheel 16 accordingly produces rotation of the sleeve 14. On the sleeve 14 there is mounted the reel support 17 bearing the supply reel 18 on which there is carried the wire or tape from which the extended coil structure is produced.

In the embodiment shown it is assumed that the coil structure is produced from wire 7.

Within the front part of the bush 13 there is rotatably mounted a bush 19 having an eccentric boring. This eccentric bush carries at its one end the teeth 20 adapted to engage with a gear wheel 21 mounted on the shaft 16a. Rotation of the shaft 16a and the gear wheel 21 causes rotation of the eccentric bush 19.

The rolling member constituted by the mandrel comprises three parts: the front part 22 with the helical groove 23, the middle portion 24, which is rotatable in the eccentric bush 19, and the rear portion 25, which is designed as a gear wheel and meshes with the fixed rim of teeth 12 on the part 10. The front part 22 passes through a guide sleeve 26. As shown by Figs. 2 and 4 the bore of this sleeve has a diameter which is larger than that of the mandrel 22. The diameter of the bore of the sleeve 26 is equal to the outer diameter of the coil structure produced from the wire 7, as shown in Fig. 2. On the front part of the fixed bush 13 there is mounted a sleeve 27 acting as winding mandrel. The rolling mandrel passes eccentrically through the sleeve 27. The bore of the sleeve 26, the wire coil structure and the sleeve 27 have a common longitudinal middle axis.

The operation of this embodiment of the invention is as follows:

The gear wheels 16 and 21 are set into operation. The gear wheel 21 rotates the eccentric bush 19, whereby a movement which is eccentric with respect to the bore of the sleeve 26 is imparted to the mandrel 22, 24, 25. Since the gear wheel 25 of the mandrel rolls over the rim of teeth 12 the mandrel is also caused to be rotated. The mandrel, therefore, as shown in Fig. 4, rolls in the direction of the arrow P¹. The wire 7 runs off from the planetary reel 18 and through a guide 28 on to the sleeve 27. The mandrel portion 22 rolls over the inner face of the coil structure being produced and by reason of the engagement between the helical groove 23 and the wire 7 conveys the coil structure towards the right in the direction of the arrow P³.

Fig. 2 shows that in the case the mean diameter of the helical groove 23 in the mandrel 22 is smaller than the mean diameter of the coil structure 7, whereas the pitch of the two, however, is the same. The coil structure is advanced in the direction of the arrow P³ in the manner already described in conjunction with the first embodiment.

What I claim as new and desire to secure by Letters Patent is:

1. In an apparatus for producing endless extended coil structures from wire or a like material, a supply reel moving with planetary motion from which the wire is withdrawn, a bush having an eccentric bore, a fixed cylindrical mandrel, a sleeve performing a rolling movement about the said mandrel and adapted to rotate within the said eccentric bore, a helical groove in the inner face of the said sleeve, an inner rim of teeth in the said sleeve, and an outer rim of teeth on the said mandrel adapted to mesh with the teeth on the said sleeve.

2. In an apparatus for producing endless extending coil structures from wire or like material, means for continuously feeding a wire, a mandrel member about which the wire is arranged, a sleeve member arranged eccentrically about the mandrel with the wire thereon, one of the members having a helical groove, and means for rotating one of the members relatively to the other to produce a rolling movement and

to effect continuous advancement and coiling and discharging of the coiled wire between said members.

3. In an apparatus for producing endless extending coil structures from wire or a like material, a supply reel moving with planetary motion from which the wire is withdrawn, a mandrel member, a sleeve member about the mandrel member and having an internal diameter greater than the external diameter of the mandrel member, said members being arranged eccentrically with respect to each other and relatively rotatable, one of the members having a helical groove therein, and means for rotating the rotatable member so that owing to eccentrical positioning of the members and the helical groove a rolling movement is effected to continuously move and coil the wire.

4. In an apparatus as claimed in claim 2, in which the sleeve member has an internal diameter equal to the outer diameter of the coil structure being produced in which the mandrel is provided with the helical groove and performs a rolling motion within said sleeve.

5. In an apparatus as claimed in claim 2, in which the sleeve member is stationary and in which a positively rotated bush having eccentric boring is provided, the mandrel being located within said eccentric boring, a gear wheel on said mandrel, and inner teeth on the said bush meshing with said gear wheel to produce a rolling motion of said mandrel with respect to said sleeve member.

6. In an apparatus as claimed in claim 2, in which the sleeve member is rotatably mounted about the mandrel and is provided on its inner surface with the helical groove which contacts the coiled wire only at one progressively moving point, the said groove and the said coil structure having different mean diameters but equal pitch.

7. In an apparatus as claimed in claim 2, in which the mandrel is fixed and in which the sleeve is rotatable and is provided with the helical groove on its inner face and performs a rolling movement about said mandrel.

ARNOLD DÖRR.
